SAFETY CONTROL FOR GASEOUS FUEL
BURNERS

William J. Russell, Jeannette, Pa., assignor to Robertshaw-Fulton Controls Company, Greensburg, Pa., a corporation of Delaware

Application December 30, 1950, Serial No. 263,648

3 Claims. (Cl. 158—130)

This invention relates to safety controls for gaseous fuel burners and more particularly to flame responsive controls for cutting off the supply of fuel to the burners in the event of flame failure.

In fuel controlling devices of this type, it is desirable to maintain a safety valve and a pilot valve open in the presence of a pilot flame and closed in the absence thereof. To this end, in the present invention, a flame responsive safety valve and a pilot valve are interconnected so that opening and closing of the safety valve causes corresponding opening and closing of the pilot valve. To provide an initial supply of fuel to establish a pilot flame to which the safety valve may respond, manually operable means cooperate with the means interconnecting the safety and pilot valves to open the pilot valve while the safety valve is closed.

In safety control devices of this type, the safety valve must pass a maximum volume of fluid with minimum throttling action when in the open position. However, with thermally responsive actuating mechanisms now known in the art, the practical amplitude through which the valve member of a safety valve can be moved is limited to a relatively small distance. Accordingly, the amount of fluid fuel which can pass through such a valve is limited by the size of the aperture formed between the valve seat and the valve member when the valve member is in open position. In the present invention, a plurality of valve seats cooperate with the valve member to provide a plurality of apertures through which the fuel may flow thus increasing the effective passage area of the valve without increasing the diameter or amplitude of movement of the valve member.

It is an object of this invention to cause complete and automatic shut off of all fuel to both main and pilot burners when the pilot flame is extinguished.

Another object of this invention is to permit flow of fuel to the pilot burner during the starting operation while preventing any flow to the main burner.

Another object of this invention is to permit control of the pilot valve by manually operable means during the starting operation and by the flame responsive safety valve during other operations.

Another object of this invention is to pass a maximum amount of fluid through a valve structure.

Another object of this invention is to eliminate throttling in a fluid controlling valve structure.

Another object of this invention is to increase the effective area of the fluid passage in a valve having a given size valve member movable through a given amplitude.

Another object of this invention is to arrange the control in compact form as a unitary construction which is adapted for manufacture at low cost and which will occupy a small space when installed in a gas appliance.

Other objects and advantages will become apparent from the following description taken in connection with the accompanying drawings wherein:

Fig. 1 is a schematic view of a safety control device

2

embodying the subject matter of this invention shown in conjunction with a gaseous fuel burner;

Fig. 2 is a schematic view of the control device shown in Fig. 1 with the parts thereof in different operating positions;

Fig. 3 is a schematic view of the control device shown in Fig. 1 with the parts thereof in still another operating position; and

Fig. 4 is a sectional view taken on the line IV—IV of Fig. 1.

Referring more particularly to Fig. 1 of the drawings, a main burner 10 is shown for location in a conventional gaseous fuel burning heating device (not shown). The main burner 10 is supplied with gaseous fuel through a pipe 12, the flow of fuel of which is under the control of a suitable thermostat 14 and a safety valve mechanism indicated generally by the reference numeral 16.

Disposed in igniting relation with the main burner 10 is a pilot burner 18 which is adapted to be supplied with fuel through a conduit 20. Flow of fuel to the pilot burner 18 is under the control of a pilot valve indicated generally by the reference numeral 22.

Actuation of the safety valve and the pilot valve is effected by condition responsive means here shown as a thermomagnetic device 24 adapted to respond to the presence or absence of a flame at the pilot burner 18 and positioned to be cooperable with the safety valve 16 and the pilot valve 22.

The safety valve 16 and the pilot valve 22 are carried by a casing 26 which is provided with an inlet chamber 28 and an outlet chamber 30 separated by a partition 32. Communicating with the inlet chamber 28 through an inlet opening 34 is a pipe 36 which is connected to a source of fluid fuel supply (not shown). Communication is maintained between the outlet chamber 30 and the thermostat 14 by a pipe 38 which extends through an outlet opening 40 formed in the casing 26.

The partition 32 is provided with a valve opening 42 through which the inlet chamber 28 is adapted to be placed in communication with the outlet chamber 30. The valve opening 42 is preferably annular in form but may comprise an annular row of ports. Surrounding the valve opening 42 and carried by the partition 32 is a valve seat 44, and also carried by the partition 32 radially inward of the valve opening 42 is a second valve seat 46. A cylindrical boss 48 is formed on the partition 32 radially inward of the valve seat 46 and is provided with a cylindrical recess for slidably receiving a valve stem 52 to which is secured a valve member 54.

That portion of the valve member 54 adjacent the periphery thereof is imperforate and forms a seating portion adapted to engage the valve seats 44, 46 to interrupt communication between the inlet chamber 28 and the outlet chamber 30. The central portion of the valve member 54 is pierced by a plurality of bores 56 which serve as passages for maintaining communication between the inlet chamber 28 and the space beneath the valve member 54.

Interposed between the valve member 54 and the partition 32 is a spring 58 which serves to bias the valve member away from the valve seats 44, 46 and into engagement with a flexible diaphragm 60 which closes the open end of the casing 26 and serves to seal the casing 26 against leakage at this point. The thermomagnetic device 24 is positioned on the side of the diaphragm 60 opposite the safety valve 16 and serves to position the valve member 54 either in its biased position or in engagement with the valve seats 44, 46.

When the valve member 54 is in its biased position as shown more clearly in Fig. 3 of the drawings, the valve member 54 will be spaced from the valve seats 44, 46 and the valve seats 44, 46 will coat with the valve mem-

ber 54 to effectively form a pair of annular orifices. The annular orifice defined by the valve member 54 and the valve seat 44 will be in direct communication with the inlet chamber 28 and the annular orifice defined by the valve member 54 and the valve seat 46 will be maintained in communication with the inlet chamber 28 through the bores 56 formed in the valve member 54. Communication is maintained between the outlet chamber 30 and both the aforementioned annular orifices through the valve opening 42. Since, in valves of the type herein disclosed, the capacity is determined by the area of the orifice defined by the valve member and the valve seat when the valve member is in open position, it will be apparent that the orifice area for a given axial displacement of the valve member 54 is substantially increased by the provision of a plurality of valve seats and by the provision of passages 56 in the valve member to insure the maintenance of communication between all the orifices and the inlet chamber 28.

The pilot valve 22 may comprise a generally cylindrical pilot valve casing 62 suitably secured to the casing 26 laterally of the safety valve 16 and provided with a centrally disposed valve opening 64 in communication with the inlet chamber 28. A valve seat 66 carried by the pilot valve casing 62 surrounds the valve opening 64 and is adapted to be engaged by a valve disc 67 to cut off communication between the valve opening 64 and the inlet chamber 28.

Extending through the valve opening 64 is a valve stem 68 which carries the valve disc 67 on one end. Secured to the other end of the valve stem 68 by any suitable fluid-tight coupling is a flexible diaphragm 70 which has its peripheral portion secured to the pilot valve casing 62 by any suitable means to seal the casing 62 against leakage at this point. The valve disc 67 is biased into engagement with the valve seat 66 by means of a spring 72 connected to the valve stem 68 and engaging the casing 62. A bore 74 is formed in the wall of the casing 62 to receive an end of the conduit 20 and thereby establish communication between the pilot burner 18 and the valve opening 64.

It is desirable that the pilot valve 22 be set in a fuel flow preventing position when the safety valve 16 is in such a position so that the safety device will be effective to shut off the gas to both the main burner and the pilot burner 18. To this end, means are provided for transmitting motion from the safety valve member 54 to the pilot valve 22 so that movement of the valve member 54 away from the valve seats 44, 46 will cause a corresponding movement of the valve disc 67 away from valve seat 66 of the pilot valve 22 against the bias of the spring 72. This means may take the form of a main lever 76 having its end portions 78, 80 overlying the safety valve 16 and the pilot valve 22 respectively. The lever 76 is pivoted intermediate its ends at 81 on a lug 82 depending from an auxiliary lever 84. One end of the auxiliary lever 84 is pivoted at 86 on a housing 87 secured to the casing 26 by any suitable means. Pivotal movement of the lever 84 about its pivot 86 is effected by manually operable means operatively associated with the free end 88 thereof as will more fully appear.

The thermomagnetic device 24 is here shown as comprising an electromagnet 90, its associated winding 92 and armature 94. The electromagnet 90 is securely mounted in a cage 96 slidably carried in a cup-shaped recess 98 formed in the housing 87 in axial alignment with the safety valve 16. The armature 94 is mounted in the cage 96 for movement relative to the magnet 90 and is provided with a cylindrical extension 99 which extends through a cylindrical guide element 100, formed in the lower portion of the cage 96, and into engagement with the end portion 78 of the main lever 76.

Interposed between the cage 96 and a collar 102 formed on the extension 99 of the armature 94 is a spring 104 which serves to bias the armature 94, 99 into engagement

with the free end 78 of the main lever 76 when the armature 94 is in its free position as shown in Fig. 1 of the drawings. The spring 104 is of such strength that it will force the free end 78 of the lever 76 into engagement with the diaphragm 60 to move the valve member 54 against the bias of the spring 58 and into engagement with the valve seats 44, 46.

The cage 96 is normally retained in engagement with the end wall 106 of the recess 98 by the bias of a spring 108 acting between the cage 96 and an internal flange 110 carried by the housing 87. Interposed between the spring 108 and the cage 96 is the free end 88 of the auxiliary lever 84. The free end 88 of the lever 84 is thus retained in engagement with the cage 96 and is movable therewith. As best shown in Fig. 4, the flange 110 may be formed with a gap 112 therein to insure freedom of movement of the main lever 76.

The winding 92 and the magnet 90 are energized by a thermoelectric device here shown as a thermocouple 114 positioned to be exposed to a flame emanating from the pilot burner 18. An electric current generated by the thermocouple 114 is generally insufficient to attract the armature 94 but is capable of retaining it in attracted position after it has been reset in such position. Consequently, manually operable resetting means is provided and takes the form of a push button 116 slidably carried in a bore 118 formed in the end wall 106 of the recess 98 in the housing 87. To retain the push button 116 in position, the outer end of the bore 118 is reduced to provide a shoulder 120 adapted to abut a flange 122 formed on the push button 116.

The cage 96 is maintained in engagement with the push button 116 by the bias of the spring 108 and movement of the push button will effect a corresponding movement of the cage 96 and its associated magnet 90. Thus, to reset the armature 94 in its attracted position, the push button 116 is depressed to move the cage 96 and magnet 90 downward, as viewed in the drawings, and bring the pole faces of the magnet into engagement with the armature 94.

Operation

Let it be assumed that the parts of the control device are in the position shown in Fig. 1 and no flame is present at the pilot burner 18 or the main burner 10. The push button 116 is manually depressed to move the cage 96 against the bias of the springs 108 and 104 while simultaneously moving the magnet 90 into engagement with the armature 94. Downward movement of the cage 96 will cause counterclockwise movement of the auxiliary lever 84 to effect a general downward movement of the pivot 81 of the main lever 76. Since the end 78 of the main lever 76 is restrained from vertical movement by the armature 94 and the valve member 54, downward movement of the pivot 81 will effect clockwise movement of the lever 76 about the end 78 thereof to impart a downward movement to the pilot valve stem 68 and its associated valve disc 67 against the bias of the spring 72.

The various parts of the control are now in the positions shown in Fig. 2 and fuel will flow from the inlet chamber 28 past the valve seat 66 of the pilot valve 22, through the valve opening 64, the bore 74, and conduit 20 to the pilot burner 18 where it may be ignited by a match or the like. When the thermocouple 114 becomes heated by the pilot flame, it will generate an electric current to energize the winding 92 of the electromagnet 90. The push button 116 may now be released to permit the cage 96 to be moved under the bias of the spring 108 into engagement with the end wall 106. Since the winding 92 of the electromagnet is now energized, the armature 94 will be retained in attracted position and will move upward with the cage 96 and the magnet 90 to the position shown in Fig. 3 retaining the spring 104 in a compressed condition.

Upward movement of the armature 94 with the cage

96 and the electromagnet 90 will remove the restraining force from the valve member 54 of the safety valve 16 and permit the valve member 54 to move away from the valve seats 44, 46 under the bias of the spring 58. It is to be noted that although the pivot 81 of the lever 76 is moved upward upon return of the cage 96 to its normal position, upward movement of the valve member 54 will cause an upward movement of the end 78 of the lever 76 to pivot the lever 76 about the fulcrum 81 in a clockwise direction to maintain the pilot valve stem 68 in depressed position with the valve disc 67 out of engagement with the valve seat 66. The various parts of the control device are now in position for steady state operation and are as shown in Fig. 3 of the drawings.

Upon failure of the flame at the pilot burner 18, the thermocouple 114 will cool terminating the supply of electric current to the winding 92 of the electromagnet 90. The deenergized magnet will release the armature 94 which will be moved under the bias of the spring 104 to move the end 78 of the lever 76 and the valve member 54 of the safety valve 16 downward. The lever 76 will be moved counterclockwise about the pivot 81 to permit the valve stem 68 and its associated valve disc 67 to move upward under the bias of the spring 72 thus causing the valve disc 67 to engage the valve seat 66 and cut off the supply of fuel to the pilot burner 18. Simultaneously, the valve member 54 will be moved against the bias of the spring 58 into engagement with the valve seats 44, 46 to cut off the supply of fuel to the main burner 10. The various parts of the control device are thus positioned as shown in Fig. 1 of the drawings and no fuel can flow to either of the burners.

It will be understood that many changes may be made in the details of construction and arrangement of parts without departing from the scope of the invention and that this description and accompanying drawings are intended by way of illustration only and are not to be construed in a limiting sense.

It is claimed and desired to secure by Letters Patent:

1. In a safety control for gaseous fuel burners having main and pilot burners, the combination of a main valve biased to open position during normal operation of the burners for controlling the supply of fuel to the main burner, a pilot valve biased to closed position for controlling the supply of fuel to the pilot burner, a lever having a pivotal support and being operatively associated with said main valve and said pilot valve, said lever being constructed and arranged to hold said pilot valve in open position while said main valve is in open position, an electromagnet, a thermoelectric device located to be heated by a flame at the pilot burner for energizing said electromagnet, an armature mounted for movement relative to said electromagnet, said armature being biased to the free position thereof and adapted to hold said main valve closed in the free position thereof while permitting said main valve to assume its biased position in the attracted position thereof, manually operable means for moving said electromagnet into engagement with said armature to attract and hold said armature in attracted position, and lever means movable with said manually operable means for moving said pivotal support to position said lever to overcome the bias of said pilot valve during operation of said manually operable means while said main valve is in closed position.

2. In a safety control for gaseous fuel burners having

65

main and pilot burners, the combination of a main valve biased to open position during normal operation of the burners for controlling the supply of fuel to the main burner, a pilot valve biased to closed position for controlling the supply of fuel to the pilot burner, a first lever, a second lever pivotally mounted on said first lever and being operatively associated with said main valve and said pilot valve, said second lever being constructed and arranged to hold said pilot valve in open position while said main valve is in open position, an electromagnet, a thermoelectric device located to be heated by a flame at the pilot burner for energizing said electromagnet, an armature mounted for movement relative to said electromagnet, said armature being biased to the free position thereof and adapted to hold said main valve closed in the free position thereof while permitting said main valve to assume its biased position in the attracted position thereof, manually operable means for moving said electromagnet into engagement with said armature to attract and hold said armature in attracted position, and means movable with said manually operable means for moving said first lever to position said second lever to overcome the bias of said pilot valve while said main valve is in closed position.

3. In a safety control for gaseous fuel burners having main and pilot burners, the combination of a main valve biased to open position during normal operation of the burners for controlling the supply of fuel to the main burner, a pilot valve biased to closed position for controlling the supply of fuel to the pilot burner, said pilot valve being disposed laterally of said main valve, a first lever, a second lever pivotally mounted on said first lever and arranged in overlying relation with said main valve and said pilot valve whereby forces are transmitted from said main valve to said pilot valve to hold said pilot valve open while said main valve is open, an electromagnet, a thermoelectric device located to be heated by a flame at the pilot burner for energizing said electromagnet, an armature mounted for movement relative to said electromagnet, said armature being biased to the free position thereof and adapted to hold said main valve closed in the free position thereof while permitting said main valve to assume its biased position in the attracted position thereof, manually operable means for moving said electromagnet into engagement with said armature to attract and hold said armature in attracted position, and means movable with said manually operable means for moving said first lever to position said second lever to overcome the bias of said pilot valve while said main valve is in closed position.
